UNITED STATES PATENT OFFICE

ERNST BRÄUER, OF VOIGTS DORF, GERMANY

TRANSMISSION OF MESSAGES BY ELECTROMAGNETIC WAVES

Application filed December 9, 1925, Serial No. 74,414, and in Germany January 25, 1924.

Applications for this invention have been filed in Germany, January 25, 1924, and June 25, 1924.

For the transmission of messages by electric waves the main problem is the separation of the message transmitted from other waves which might be stronger. During the transmitting of a simple wave the elimination of disturbances is obtained, and by the 10 constancy of this wave and the damping of the antenna together with oscillating circuits switched onto the receiver, it is possible to practically separate waves, the lengths of which differ by some percents. As, however, 15 the range of the wave lengths at disposal is limited with regard to the minimum value as well as to the maximum value it follows, that only a limited number of messages can be sent simultaneously through the 20 space. By improving the tuning the possible number of messages may be increased but this is soon limited again when the succession of the different wave-lengths which carry the different messages becomes all too 25 close, the tuning of the receiver must be so sharp that the difficulty of finding a message increases to an impossibility. It has, therefore, been proposed to use as carrier for the signals, instead of a simple wave, a wave 30 varying two or more times. Such a modulated wave consists, for instance, of a high frequency of 1,000,000 oscillations, which increase however in one hundred thousandth of a second from zero to a maximum value 35 to drop again to zero. The second frequency has in this case a period of vibrations of 100,000 per second. The value of the maximum amplitude determines in first instance the signal. In the telegraphic signs this 40 maximum amplitude is either equal to a constant value, e. g. as long as the sign lasts, or equal to zero in the interval between two consecutive signs. In the wireless telephony the maximum amplitude varies in such a 45 manner that its value adapts itself to the course of the vibrations of the human speech. By employing such a second variation the number of the possible communications is increased from n to almost n^2 . For a triple 50 wave the number would increase to n^3 . It

has been found that difficulties arise already at a modulated wave, e. g. at two-fold variation.

This invention has for its object to obviate these difficulties in such a manner that, under certain conditions, not only a two-fold but even a three-fold variation can be practically employed. It has been found, that at the multiple wave telegraphy (or telephony) disturbances become prejudicial in a higher degree. The problem consists in separating the waves of the same high-frequency, if the variation frequency is different, for instance at the high frequency 1,000,000, to separate intermediate frequencies of 80,000 and 100,000. With this object in view the receiver energy is in first instance sifted by means of oscillating circuits which are syntonized to high frequency (in the example given 1,000,000), whereupon a rectification of the current is produced which gives an energy oscillating in the variation frequency. This energy acts upon oscillating circuits which are syntonized to the frequency which exists in the signal (in the example 100,000) and eliminate interfering frequencies (in the example 80,000). On this follows rectification and consequently reception of the signal which, according to its kind, is either recorded by the Morse receiver or rendered audible in the telephone.

If there exists an interfering high frequency of great energy and of the same oscillation period 1,000,000, it will not be able to enter into the circuits of intermediate frequency, but, if it should be suddenly interrupted, it will give to the intermediate frequency circuits an impulse to vibrate and thereby cause disturbance. This disturbance is common in the multiple telegraphy, which has hitherto not been discovered. According to the invention it is avoided by the insertion of an element into the circuit which element will weaken the interfering energy, before the same can give an impulse to the intermediate frequency circuits, so much that this interfering energy is no longer essentially stronger than the energy of the signal. A conducting element adapted for this purpose is preferably any glow cathode tube

and, under certain conditions, also gas discharge tubes which possess the property to suppress energies which exceed a predetermined value.

Such a glow cathode tube, the saturation current of which is not essentially higher than the signal energy is, for instance, inserted at its place in the following manner into the receiving apparatus: Upon the high frequency oscillation circuits and eventually upon an amplifier follows a rectifier which transmits the signal energy as oscillations of a wave current. As a strong interfering energy of equal high frequency would result in the signal representing only comparatively weak fluctuations of a high current value, an intercepting current portion behind the rectifier would really neutralize the signal energy. For this reason the wave current is, according to the invention transformed, directly behind the rectifier, into an alternating current, preferably by an aperiodic inductive transmission. Then follows the device for eliminating the interfering energy which cuts off directly above the amplitude of the signal the interfering energy perceptible at this instant only as current shock, and then follow the circuits synchronized to the intermediate frequency.

Two diagrams of suitable receiving circuits are shown, by way of example, in the accompanying drawings.

Fig. 1 represents a simple receiving system.

Fig. 2 represents a receiving system for greater sensitiveness.

1 is the receiving antenna; 2, a circuit which is tuned to the wave length; 3, a valve used as detector; and 4 an aperiodic transformer arranged between the anode circuit of the valve 3 and the grid circuit of a valve 5 which acts as a limiter and at the same time as an amplifier. The circuit 6, which is tuned to the amplitude frequency, passes the energy, through the medium of a transformer 7, on to a second rectifying valve 8 the anode circuit 10 of which contains the phones 9. A condenser is arranged across the terminals of the latter.

When a very powerful receiver is required, the arrangement shown in Fig. 2, which contains six valves, may be resorted to. In this case the receiving antenna 11 is connected to earth through a resistance 12 and direct to a high-frequency amplifier 13. The connection between the latter and another high-frequency amplifier 17, which also acts as a preliminary limiter, may contain resistances 14 and 15 and a condenser

16. In and behind the anode circuit of the valve 17 the high-frequency tuning circuit 18 is arranged. The transformer 19 passes the impulses on to the grid of a valve 20 which rectifies the high frequency and produces a wave train whose oscillations are de-

termined by the amplitude frequency which, as already described, is a frequency lying between the high frequency and the signal frequency. An aperiodic transformer 21 converts the impulses into an alternating current which passes through a limiter 22. The anode of the latter is connected to a circuit 23 which is tuned to the intermediate frequency, the latter being rectified by a valve 24 so as to produce the signal. Another transformer 25, and a low-frequency amplifier 26 may be arranged between the valve 24 and the phones 27.

Even in this arrangement the interfering energy might, under certain conditions, make itself perceptible in a disagreeable manner and choking of the intermediate frequency might occur, if the damping of the circuits, especially of the high frequency circuits, is not sufficiently strong. This has really not yet been sufficiently recognized in the multiple wave telegraphy, although similar phenomena have been known for a long time in the simple wave telegraphy. It is true that these phenomena manifest themselves in another manner.

It is not possible to build an oscillating circuit, especially an antenna, with such little damping that a normal high frequency wave, the amplitude of which can for instance be influenced by the human speech, oscillates through in such a degree, and thus chokes the human speech, as such a very great number of high frequency oscillations acts upon one single oscillation of speech. In the double-wave telegraphy this is however not at all the same, as the intermediate frequency is not at all insignificantly little with regard to the high frequency. In the example given it was ten times less. Whilst, therefore, in the simple wave telegraphy, an oscillating through and choking of the signal can occur only in special arrangements comprising artificially reduced damping (glow cathode tubes with return coupling) the oscillating through and the choking of the intermediate frequency becomes perceptible already at a damping equal to $1/10$, so that it is necessary to specially take these conditions into consideration.

According to the invention the damping of the circuits is adapted every time to the relation of the high frequency to the intermediate frequency, or of the intermediate frequency to the signal frequency. By taking this point into consideration it is possible to obtain by rather high damping not only two-fold but even three-fold variation of the waves and thereby two-fold or three-fold selectivity. Three-fold variation according to the invention is certainly always possible in the telegraphy. The telegraphy frequency can be increased to the value of several hundreds per second without the danger that abnormal damping should occur and through the

same evident reduction of the number of communications. In this case a damping will be sufficient like that which is found to be practical for other reasons.

5 The application of the three-fold variation is not only possible for the telegraphy. In the telephony two-fold variation is possible, under all practical conditions, for the practical dampings. In a special field however, especially if short e. g. very high frequency waves are used, a three-fold variation and consequently an enormous increase of the number of communications will also be possible in the telephone-transmission.

10 15 In order to obtain desired damping a resistance can be inserted into the antenna or into the oscillating circuit. The inserted resistance is preferably made variable as in this case the selectivity can be adjusted at 20 any time to the value determined by the interferences.

25 It is not my intention to limit my invention to the details of the method described above nor to the means shown by way of example in the accompanying drawings as any practical variations and modifications falling under the general idea of my invention might be applied.

I claim:—

30 A method for the transmission of wireless messages from antennæ and for selectively receiving these messages from any one of said antennæ consisting in successively modulating lower intermediate frequencies 35 upon a high frequency carrier wave to obtain a multiplicity of messages, selectively receiving and detecting this successively modulated carrier wave free from interfering signal waves so that the energies received become almost zero at the zero points 40 of the transmitting waves, by damping the disturbing energies approximately to the amount of the signal amplitude at each stage 45 of demodulation in advance of the respective tuned circuit of lower frequency.

In testimony whereof I affix my signature.
ERNST BRÄUER.
